UNITED STATES PATENT OFFICE

162,976

CLOCK

George W. Nelson, New York, N. Y., assignor to Howard Miller Clock Company, Zeeland, Mich.,
a corporation of Michigan

Application March 20, 1950, Serial No. 8,654

Term of patent 14 years

(Cl. D42—7)

To all whom it may concern:

Be it known that I, George W. Nelson, a citizen of the United States, residing at New York city, in the county of New York and State of New York, have invented a new, original, and ornamental Design for Clock, of which the following is a specification, reference being had to the accompanying drawing, forming part thereof.

Fig. 1 is a front elevation of a clock showing my new design, and

Fig. 2 is a side elevation of the same.

I claim:

The ornamental design for a clock, substantially as shown.

GEORGE W. NELSON.
